UNITED STATES PATENT OFFICE.

STANLEY SZASTALO, OF NEW YORK, N. Y.

SHOE-FASTENING DEVICE.

Application filed October 29, 1924. Serial No. 746,484.

This invention relates to a device for holding together the two wings of the upper of the shoe, the invention having for an object the provision of a novel device of this sort which may be applied more quickly than the ordinary laces can be tightened.

For further comprehension of the invention, and of the objects and advantages thereof, reference will be had to the following description and accompanying drawing, and to the appended claims in which the various novel features of the invention are more particularly set forth.

Fig. 1 of the drawing is a plan view of a shoe having my improved device applied thereto.

Fig. 2 is a fragmentary transverse sectional view taken on the line 2—2 of Fig. 1.

Fig. 3 is a fragmentary perspective view of the frame element of the device.

Figure 4 is a perspective view of a shoe having my improved device applied thereto.

In the drawings the reference numeral 10 designates the two wings of the upper of an ordinary low shoe, these wings being arranged in the manner common to lace shoes, that is to say with their adjacent edges meeting, or approximately meeting. To make provision for receiving the fastening device which I employ instead of the usual lace each of the wings has attached thereto a metal strip 12, these strips extending along the adjacent edge of the wings, and being attached to the said edge of the wings along their adjacent sides, having the opposite sides free to prevent confining elements under which the edges of the fastening device engage.

This fastening device comprises an elongated strap which is indicated generally at 15 in Figs. 1 and 2 and has its side edges turned backward under the body of the strap as at 16, these inturned flanges 16 being adapted to engage freely under the said remote sides of the strip 12 to retain the fastening device against displacement. The said fastening device preferably tapers in width from end to end, while the strips 12 are arranged so as to have their remote side edges tapered with respect to one another in correspondence with the taper of the said device, this arrangement facilitating insertion and removal of the device and causing the wings of the shoe to draw together by pressing the said device further upward along the edges of the wings. The fasten-

ing device may be formed from a metal frame element over which is stretched a covering of like material to the shoe. This frame element comprises a central longitudinally extending member or backpiece 15 from which the ribs 15^a extend on opposite sides, the ends of the ribs being backturned to provide for the flange 16 while the tips of the ribs may be united by the longitudinal members 15'. As will be understood, this frame may be readily formed by stamping a suitable blank and bending the side edges thereof. The construction of the frame provides for a certain degree of longitudinal resiliency of the strap 15, while maintaining sufficient stiffness for ready manipulation when being inserted in place. It will be understood of course that the straps may likewise be covered with a facing material similar to that of the shoe upper.

To secure the strap 15 in place a flat spring 18 is attached thereto near the upper end thereof, this spring being riveted or otherwise attached to the said strap midway between its ends as at 19 and extending transversely of the strap. Fixed to the ends of this spring are studs 20 which project downward through apertures 21 in the strap and are adapted to engage in apertures 22 in the strips 12, there being preferably a series of these apertures extending along each strip so as to permit of the strap being secured in place in longitudinally adjusted positions.

In order to move the studs 20 out of the apertures 22 I provide a pair of levers 25 which are fulcrumed at one end adjacent the centre of the strap, and to the latter, and which diverge away from one another and pass under the respective ends of the spring 18, said studs 20 have knobs 26 at their upper ends.

As shown in Fig. 1 of the drawing the levers 25 extend in somewhat the manner of crossed shoe laces, while the strap 15 have placed thereon dummy laces 28, which are arranged in the manner of the usual laces employed in securing the two wings of the shoe together.

It is believed that the manner of use of my improved device will be readily understood from the above description, it being apparent that the engagement of the flanges 16 under the sides of the strips causes the edges of the wings to be held against displace-

ment, while the studs prevent the device slipping from place. When these levers 25 are drawn toward one another they exert a camming action on the ends of the spring 18 and cause the studs 20 to be withdrawn from the apertures 22 to permit of the device being removed by sliding it off the strips 12.

Having thus described my invention what 10 I claim as new and desire to protect by Letters Patent of the United States is as follows:—

1. In a shoe, a pair of strips extending along the edges of the shoe wings, and a 15 strap element covering said strips and having side flanges engaging under the remote edges of said strips, and means for securing said strap element to said strips, comprising a spring fastened to the strap element, and 20 studs on the ends of said spring engaging in apertures in the said strips.

2. In a shoe, a pair of strips extending along the edges of the shoe wings, and a 25 strap element covering said strips and having side flanges engaging under the remote

edges of said strips, and means for securing said strap element to said strips, comprising a spring fastened to the strap element, and 30 studs on the ends of said spring engaging in apertures in the said strips, and movable elements carried by said strap for moving said studs out of the said apertures.

3. In a shoe, a pair of strips extending along the edges of the shoe wings, and a 35 strap element covering said strips and having side flanges engaging under the remote edges of said strips, and means for securing said strap element to said strips, comprising a spring fastened to the strap element, and 40 studs on the ends of said spring engaging in apertures in the said strips, and movable elements carried by said strap for moving said studs out of the said apertures, said elements comprising levers fulcrumed on the strap and passing under the ends of said 45 spring.

In testimony whereof I have affixed my signature.

STANLEY SZASTALO.
